Specification of Letters Patent.

Patented Oct. 12, 1915.

Application filed April 4, 1914. Serial No. 829,657.

To all whom it may concern:

Be it known that I, ALVIA F. WISE, a citizen of the United States, residing at Columbus, in the county of Franklin and State of Ohio, have invented certain new and useful Improvements in Combination-Switches, of which the following is a specification.

My invention relates to combination switches adapted for use in completing electric circuits. This switch is constructed primarily to prevent unauthorized persons from closing the circuit and it is, therefore, particularly adaptable to the ignition circuit of motor vehicles.

The essence of my invention resides in the provision of a switch in which a number of movements are necessary to effect a closure and these movements control mechanism to which the operator does not normally have access. It is, therefore, my aim to provide the authorized manipulator of the switch with the correct combination of movements and through these movements only may the switch be closed.

The main object of my invention resides in the provision of a plurality of switch devices all adapted to be electrically connected, one of the members forming these switch devices being movably mounted with respect to its complemental member. A structure is then provided for giving a lost motion connection between the operating dial and these movable switch members. All of the switch members forming a portion of each of the switch devices are so mounted and arranged with respect to their lost motion connecting means that it requires a predetermined order of movements of the dial to effect a complete closure of the circuit.

Another object of my invention is to so construct the device that it may be readily applied to a motor vehicle in a convenient position for the operator's manipulation. By providing this structure in which it is necessary that a predetermined order of movements are necessary, the use of a key or similar types of circuit closing means is dispensed with.

Other objects of my invention will become more apparent after a detailed description of the accompanying drawings, in which similar characters of reference designate corresponding parts, and in which:

Figure 1 is a central vertical section of my

combination switch, Fig. 2 is a section taken on line 2—2 of Fig. 1 and looking in the direction of the arrows, Fig. 3 is a detail side elevation, partially in section, of a ratchet wheel forming a portion of each movable switch member, Fig. 4 is a front view of the structure shown in Fig. 3, Fig. 5, 6 and 7 are detail views in perspective of the main portion of the clutch structure used by me, Fig. 8 is a top plan view of my switch member showing the casing in section, and, Fig. 9 is a face view of the structure shown in Fig. 8.

In illustrating my invention, I have shown the same embodied in such structure that it may be readily and conveniently applied to the dashboard of a motor vehicle. However, the manner in which it is mounted does not form any portion of this invention, as it must be apparent that the device is applicable to all electric circuits adapted to be opened and closed. In the drawings, there is shown a face member 1, preferably of circular form and being provided with a shoulder portion 2. Upon this face member is adapted to be mounted all of the controlling mechanism and the same is then inclosed in a metallic casing such as is shown at 3. The face member 1 is also centrally apertured to rotatably receive a shaft 4 rigidly carrying a dial member 5 by means of the cotter pin 6. This dial member is shown more clearly in Fig. 9 and is provided with a plurality of finger openings 7 concentrically arranged about the periphery and each of these apertures is desirably associated with some reference character, such as the numerals shown in Fig. 9. The face member 1 is also provided with a stop 8 which may be used as a reference point in operating the switch.

The switch itself is preferably comprised of a plurality of switch devices, each formed between stationary and one relatively movable member. The number of these switch devices is immaterial, as it is evident that, as their number increases, the difficulty of operation also increases. The movable members forming a portion of all of these switches are mounted upon the shaft 4, while the stationary members are rigidly carried by the stationary frame structure confined within the casing 3. This stationary frame structure is preferably formed of some insu-

lating material, such as the portions 9 and 10 held between the inner face of the face member 1 and an inner disk 11 by means of a plurality of bolts 12. This inner disk 11 is also centrally apertured to give a bearing for the inner end of the shaft 4. Upon the upper member 9 of the supporting framework, are mounted a plurality of stationary contact arms 13, the arrangement being such that a contact arm projects downwardly from each side, as is clearly shown in Fig. 2. The first of these contact arms is in electrical connection with what may be termed the service wire 14. This first set, together with the remaining sets of contact arms, are connected to each other by means of the wires 15 and 16 clearly shown in Fig. 8. Co-operating with these stationary arms 13 are two relatively movable switch arms 17 carried by blocks of insulation 18 and ultimately in control of a central shaft 4. These movable switch arms are located apart distances corresponding to the location of the stationary arms 13 and the two arms forming each set are electrically connected to each other by means of a wire or cross strip 19 shown in Figs. 2 and 8.

In order that the movable switch members may be temporarily held in any adjusted position, I have provided a ratchet wheel 20 of the type shown in Figs. 3 and 4 for each switch device. These ratchet wheels are provided with a plurality of apertures 21 any one of which may accommodate the pin shown at 22. Further, these ratchet wheels are all centrally bored and are provided with elongated hubs such as shown at 23. These wheels are all mounted in the relation shown in Fig. 1 to coöperate with balls 24 normally pressed toward the ratchets by means of springs 25 confined within a suitable housing structure such as is shown at 26 as being carried by the lower member 10 of the general framework. The hub portions 23 are provided to give a firm bearing of the ratchets upon the shaft 4, but it is to be understood that these ratchets are rotatably mounted upon this shaft. All of the metal parts adjacent any of the contact arms are securely insulated by means of the bushings 27 and the disks 28 and 29. This structure prevents the jumping of the current from one portion of the mechanism to another. Coöoperating with each of the ratchet structures, is a collar member designated by numerals 30, 31 and 32 shown in Figs. 5, 6 and 7. All of these collar members are rigidly mounted upon the shaft 4 and are each provided with cut-out portions 33, these cut-out portions varying in length. In their assembled relation upon the shaft 4, the cut-out portions 33 of the collar members are caused to engage the pins 22 on each of the ratchet wheels 20. It will thus be apparent that as the shaft 4 is rotated by rotation of the dial 5, the pins 22 are successively brought into engagement with one of the shoulders formed by cutting away of the portions 33. After sufficient rotation is given the shaft, all of the ratchet wheels 20 may be in motion at the same time. However, should the direction of rotation be reversed, the switch device to the left of Fig. 1 will come into motion first because of the collar member 32 having the smallest cut-out portion 33. Continued rotation will bring the second switch member into play and finally the switch member to the right of Fig. 1, will be given motion.

From the above description, it will be apparent that a known order of movement of the operating dial 5 will be necessary. A detailed operation of the device is as follows: The dial 5 is given a rotary motion a distance sufficient that one of the switch devices will come into operating relation. In other words, the stationary terminals 13 and the movable terminals 17 are both in electrical engagement. This is because the pin 22 of the first switch has come into engagement with one of the shoulders formed by the cut-away portions 33 formed in the member 30. After the first switch member is in its correct position, reverse movement is imparted to the dial 5 and the cut-out portion 33 of the collar member 30 is long enough so that the shoulder at the opposite end of this clutch portion does not come into engagement with the pin 22 on its respective ratchet, but a similar engagement by the pin 22 is had on the succeeding ratchet. In other words, the pin 22 on the succeeding ratchet is engaged by the shoulder of the cut-out portion of the collar member 31 and the second movable switch portion is then given a rotary motion to the exclusion of the first one already set in operative position. The required movement in this case may be three or four or five notches on the ratchet, as the case may be, depending upon what aperture 21 the pin 22 is located in. After the second switch device has been brought into its operative position, the motion of the dial 5 is again reversed and the last switch device is closed by a similar arrangement of the pin 22 on the remaining ratchet with the shoulder formed by the cut-out portion 33 in the collar member 32. However, it is necessary that the operator know exactly how many spaces each movement should have, for it is obvious that if, after the first switch device has been closed, too great a movement of the dial 5 will again cause its disengagement. The combination of movements may be changed whenever desired, by changing the position of the pins 22 in their respective apertures. By means of the spring pressed ball 24, the ratchets may be all temporarily held in their positions with a sufficient degree of

security to withstand such shocks as may be common to motor vehicles. The combination of movements may further be changed by adjusting one or more of the collar members 30, 31 and 32 upon the central shaft 4. When all of the switch devices are in their correct positions, a current may enter through the lead 14 and into the first of the stationary terminals 13 of the first switch. At this point this current enters one of the movable contacts 17 of the first switch and through the wire 19 to the other movable contact element of the same switch. Here it is transferred to the succeeding switch by means of the wire 15, passing through the same arrangement of contacts and finally into the last set by means of the wire 16. At this point, it may return by means of the wire 34. After the wires leave the casing 3, they are usually confined within a metallic tube or other tamper-proof construction, but this latter feature has not been shown.

What I claim, is:

- 25 1. A combination switch comprising a plurality of switch devices, each switch device including a rotatable switch member, a central shaft upon which said members are loosely mounted, means for temporarily holding said members in any position, a collar for each switch device rigidly mounted on said shaft, and lost motion connecting means between each collar and its respective switch member so that each collar may be given a partial revolution without rotating its switch member, said connecting means being arranged to have different amounts of lost motion.
- 30 2. A combination switch comprising a plurality of switch devices, each switch de-

vice including a rotatable switch member, a shaft upon which said rotatable switch members are loosely mounted, and a lost motion connecting means between said switch members and said shaft so that said shaft may be given a partial rotation without causing engagement of the connecting means, said connecting means being arranged to have different amounts of lost motion.

50 3. A combination switch comprising a plurality of switch devices, each switch device including a rotatable switch member, a shaft upon which said rotatable switch members are loosely mounted, a collar for each switch device rigidly mounted on said shaft, all of said collars being provided with a cut out portion said cut-out portions being of varying sizes, and a pin connection between each of said cut out portions and the respective switch members.

55 4. A combination switch comprising a plurality of switch devices, each switch device including a rotatable switch member, a ratchet wheel forming a portion of each switch member, a shaft upon which said ratchet wheels are loosely mounted, a spring pressed ball engaging each of said ratchet wheels to temporarily hold them in any position, a collar for each switch member rigidly carried by said shaft, each of said collars being provided with a cut-out portion, and a pin carried by each ratchet adapted to enter the cut-out portion of said collars.

60 70 75 In testimony whereof I affix my signature in presence of two witnesses.
